LAMP SHADE

Bozidar M. Von Serda, 9304 Santa Monica Blvd.,
Beverly Hills, Calif. 90210

Filed Aug. 26, 1974, Ser. No. 500,325

Term of patent 14 years

Int. Cl. D26—05

U.S. Cl. D48—16 D

Fig. 4

Fig. 5

Fig. 6

Fig. 7

FIG. 1 is a perspective view of a lamp shade, showing my new design;

FIG. 2 is a side elevational view thereof taken from the direction of arrow 2 in FIG. 1;

FIG. 3 is a bottom plan view;

FIG. 4 is a perspective view of a modified form in which the individual cylinders are longer;

FIG. 5 is a side elevational view thereof from the direction of arrow 5 in FIG. 4;

FIG. 6 is a bottom plan view; and

FIG. 7 is a cross-sectional view taken on line 7-7 of FIG. 4.

I claim:

The ornamental design for a lamp shade, substantially as shown and described.
